MOTOR WITH FLUID ACTUATED VALVE

Fritz Tolkien, Hanover, Germany

Application May 27, 1929, Serial No. 366,394
In Germany May 26, 1928

6 Claims. (Cl. 121—157)

(Granted under the provisions of sec. 14, act of
March 2, 1927; 357 O. G. 5)

This invention relates to steam engines having a floating slide valve for controlling the admission and exhaust of steam, said slide valve being operated by steam which acts on differential pistons comprising a smaller and a larger piston at each end of the valve which work in corresponding reversing chambers in the slide valve casing, the slide valve being held in each of its end positions by steam supplied to the 10 smaller differential piston at each end in turn. The slide valve is moved out of the end position by supplying steam to the larger differential piston at the other end. This movement of the slide valve is however only short, for after 15 moving a short distance, the valve shuts off the steam supply to the larger differential piston, so that after the expansion of this steam a condition of equilibrium is produced between the steam pressure acting on the small piston at one end 20 of the slide valve and on the larger piston at the other end of the slide valve and the slide valve thus comes to rest in a position intermediate the end positions, in which the valve cuts off the supply of steam to the cylinder. The 25 steam cut-off is determined by the time taken by the valve to reach the position of equilibrium, so that by regulating the movement of the slide valve, the steam cut-off can be varied.

The present invention has for its object to enable this cut-off regulation to be effected within the entire range from zero to 100 per cent, with the utmost accuracy and reliability. According to the invention positively controlled members such as valves are provided, which regulate the 35 timing of the admission of steam to the larger differential piston of the slide valve which moves the slide valve into the steam cut-off position.

The slide valve is moved out of this steam cut off position, in which the exhaust is still open, 40 into its end position for admitting steam to the other end of the engine cylinder, by means of steam admitted in a known manner to the smaller piston of the slide valve on the same end as the larger differential piston which has moved the 45 valve into the intermediate position. Both the differential pistons at this end are now under steam pressure and the valve is caused to travel further into its end position, with the steam inlets and outlets of the cylinder reversed by 50 exhausting the steam acting on the smaller differential piston which has hitherto prevented this movement.

The invention is illustrated in various constructional forms in the accompanying drawings, 55 in which

Fig. 1 shows a constructional form of the invention, with the slide valve in its right-hand position with the working piston moving to the right.

Fig. 1b is a section through a detail.

Fig. 2 shows the slide valve in the steam cut off position.

Fig. 3 shows the slide valve in the left-hand end position, the working piston of the engine moving to the left.

Fig. 4 shows the slide valve in the position on which it cuts off the steam supply during the movement of the working piston from right to left.

Referring to the drawings, the working piston *b* moves in a steam cylinder *a*, to which steam is supplied from a steam inlet *E* through pipes *a*¹, *a*² and a slide valve casing *c* in which slides a piston slide valve comprising two cylindrical portions *d*¹ and *d*² connected together by a rod *d*, to which are also attached differential pistons *e*, *e*¹, *e*² and *e*³, which move in reversing chambers *f*, *f*¹, *f*² and *f*³ in the slide valve casing. The steam passes into the cylinder between the larger differential pistons *e*¹ and *e*² and the slide valve parts *d*¹ and *d*² through the cylinder admission ports *a*³ and *a*⁴, respectively. The exhaust steam escapes from the cylinder *a* through ports *h*¹, *h*², respectively into the valve casing between the parts *d*¹ and *d*² and is then led away through an exhaust steam connection *k* to an outlet *A*. The valve mechanism just described is known. It is likewise known to hold the valve fast in its end positions and also, by admitting steam to the various controlling chambers, to move the slide valve intermittently in such a way that it is first brought into its cut-off position in which it interrupts the steam admission to the working cylinder, and then passes into its end position, in which the steam paths to the working cylinder are reversed. The cut-off can be regulated by causing the valve to move sooner or later into its cut-off position.

In order to obtain satisfactory cut-off regulation between zero and 100 per cent, it is necessary to control the first portion of the piston valve movement in such a manner that the valve comes to rest with certainty into the required cut-off position. For this purpose two control valves *s*¹ and *s*² are provided, hereinafter designated admission control valves.

These admission control valves communicate through steam pipes *m* and *m*¹ with the chambers *f*¹ and *f*² of the slide valve casing, in which the larger differential pistons *e*¹ and *e*² work, which move the slide valve into the steam cut-off posi-

tion. The admission control valves are actuated as hereinafter described. The differential pistons e and e^3 are supplied with live steam under the control of a small distributing slide valve t^1 5 and a reversing valve t^2 housed in separate compartments in a common casing r , said compartments being on either side of a partition having ports r^8 and r^9 . Steam is supplied to the casing r through a pipe r^{11} , which can be shut off by a 10 stop valve V .

The valve t^1 is reciprocated by a crank 21 on the engine crankshaft 121 which crank is connected by a connecting rod 22 to the valve spindle 23, so as to place the ports r^8 and r^9 alternately 15 in communication with the pipe r^{11} . The valve t^2 is actuated by the hand lever 24 pivoted on a fixed bearing member 25 and connected to the valve spindle 26 by means of a link 27.

In the position shown in Fig. 1 the steam supplied 20 through the pipe r^{11} to the casing r passes through the port r^8 and the compartment of the reversing valve t^2 through the port r^6 and the pipe n connected therewith into the reversing chamber f , where it acts on the piston e to hold 25 the slide valve in the right-hand end position. When the distributing slide valve t^1 is displaced during the rotation of the engine shaft, so that it covers the port r^8 and uncovers the port r^9 , as shown in Figs. 3 and 4 steam from the pipe r^{11} 30 passes through the compartment of the slide valve t^1 , the port r^9 , the port r^3 and the pipe n^1 to the reversing chamber f^3 at the other end of the slide valve and then acts upon the differential piston e^3 .

The reversing valve t^2 can be moved from the 35 position shown in Fig. 1 to the position shown in Fig. 1b by moving the hand lever 24 into the position indicated by the centre line 241 in Fig. 1, to interchange the steam paths for the controlling 40 steam with one another as shown in Fig. 1b. By this means the direction of revolution of the engine can be reversed without adjusting the operating means of the valve t^1 . The admission control valves s^1 and s^2 receive steam from the pipes 45 r^1 and r^5 , the former being connected to the pipe n^1 and communicating through the latter with the casing r through the ports r^2 and r^3 . The pipe r^5 branches off from the pipe n and communicates through it and through the port r^6 50 with the casing r . Each of the admission control valves s^1 and s^2 is therefore connected to a steam pipe connected to the reversing chamber at the other end of the slide valve, so that when the reversing chamber f on the left-hand side receives 55 steam, the admission control valve s^2 receives steam through the pipe r^5 , and conversely, when the chamber f^3 receives steam the admission control valve s^1 receives steam through the pipe r^1 . In the position illustrated in Fig. 1, the admission 60 control valve s^1 is evacuated, because the pipe r^1 communicates through the ports r^3 and r^9 with the exhaust port r^{12} in the casing r . Similarly in the opposite position of the distributing valve t^1 , the admission control valve s^2 is evacuated 65 through the pipe r^5 , the ports r^6 and r^8 and the exhaust port r^{10} in the casing r .

The reversing chambers f^1 and f^2 are evacuated 70 through the pipes o and o^1 . At one end of the valve rod is arranged a small piston e^4 , which moves in a dash pot piston e^5 , which moves with a certain amount of clearance in the chamber f^5 in the slide valve casing, the ends of which communicate through pipes r^4 and r^7 and the pipe n^1 and n , respectively with the valve casing r .

In Fig. 1 the working piston b is located in a

central position and the slide valve is in a position to allow live steam to pass through the inlet port a^3 behind the piston, while on the other side of the piston the exhaust steam escapes through the port h^2 . The positively driven distributing slide valve t^1 is in its left hand end position and allows steam to enter the reversing chamber f through the stationary reversing valve t^2 and the pipe n to act on the differential piston e . The reversing chamber f^3 communicates through the pipe n^1 and the ports r^3 and r^9 with the exhaust r^{12} . The slide valve is therefore held fast in the right-hand end position. Through the pipe r^7 connected to the slide valve casing r the dashpot piston e^5 is likewise supplied with steam. For 80 moving the slide valve into the steam cut-off position the valve s^2 is opened and permits live steam to enter from the pipe r^5 into the pipe m^1 into the reversing chamber f^2 . The admission control valves s^1 and s^2 are opened by means of cams y , y^1 , respectively, rotated by a shaft w , 85 against the action of closing springs s^3 , s^4 .

The shaft w is rotated by means of a bevel gear 28 fixed on it and meshing with a bevel gear 29 fixed on one end of a shaft 30, on the other end of which is fixed a bevel gear 31 meshing with a bevel gear 32 fixed on the engine crankshaft 121, the transmission ratio of the bevel gearing being such that the shaft w is rotated at the same speed as the crankshaft. 90

The cams y and y^1 are adjustable, as herein-after described, so that they can open the associated admission control valve earlier or later as desired, for the purpose of regulating the cut-off. If, the admission control valve s^2 is opened, 95 the slide valve being in the position shown in Fig. 1, so that through the pipe m^1 steam is supplied to the reversing chamber f^2 of the differential piston e^2 , the area of which is approximately twice as great as the area of the smaller 100 differential piston e , since the same steam pressure prevails in the two reversing chambers f and f^2 , the slide valve is moved to the left and shuts off the supply of live steam to the reversing chamber f^2 by means of the differential piston e^3 . The steam enclosed in the reversing chamber f^2 then expands, the slide valve continuing its motion to the left against the force of the steam acting on the differential piston e which retards the motion of the slide valve until 105 the pressure in the reversing chamber f^2 is equal to about half the pressure in the reversing chamber f when a state of equilibrium of the slide valve is attained. The slide valve is now in the 110 cut-off position shown in Fig. 2 in which the cylinder admission port a^3 is covered by the valve part d^1 . In order to make this position independent of the action of inertia forces and friction, for the purpose of satisfactorily fixing the 115 position of the slide valve, the dashpot piston e^5 is provided. As shown in Figure 2, the piston e^4 of the slide valve bears against the left-hand inside wall of the dashpot piston e^5 , which is held fast in its right-hand end position by live steam supplied through the pipe r^7 . Since steam can 120 no longer pass into or escape from the reversing chamber f^2 and that of the steam in the chamber f^3 acting on the dashpot piston e^5 remains constant, the valve is satisfactorily held fast in the 125 steam cut-off position.

In Fig. 2 the portion d^2 of the slide valve still leaves the exhaust passage h^2 of the working cylinder uncovered, so that compression is only effected after the passage h^2 is covered by the working piston b . By the time the piston b has 130

reached the dead centre position the distributing slide valve t^1 has moved into the return stroke position in which it allows live steam to flow to the reversing chamber f^3 through the pipe n^1 while the right-hand side of the dashpot piston e^5 is supplied with steam through the pipe r^4 , and the steam from the reversing chamber f passes to the exhaust port r^{10} through the pipe n , the reversing slide valve t^2 , the port r^8 and the distributing slide valve t^1 .

The main slide valve d^1, d^2 is thereby moved into the left-hand end position shown in Fig. 3 and the return stroke then commences, the cut-off being now under the control of the admission control valve s^1 . When the valve s^1 is opened by the cam y , steam is supplied through the pipe r^{11} , the chamber of the distributing slide valve t^1 , the port r^9 , the chamber of the reversing valve t^2 and the port r^3 to the pipes r^1 and m and thence to the reversing space f^1 to act on the larger differential piston e^1 . The main slide valve is thereby moved to the right into the position shown in Fig. 4 in a similar manner to that already described in connection with the piston e^2 , the small piston e shutting off the supply of steam to the reversing space f^1 through the pipe m and the part d^2 of the main slide valve covering the admission passage a^4 of the working cylinder and cutting off the steam supply to the cylinder. The main slide valve is held fast in this position by the dashpot piston e^5 to which steam is supplied through the pipe r^4 which holds it in its left-hand end position, the dashpot piston serving as a stop for the piston e^4 . Hence the dashpot piston e^5 , in conjunction with the piston e^4 , also ensures that the main slide valve during the return stroke will move into the required cut-off position shown in Figure 4.

The distributing slide valve t^1 then moves into the position shown in Fig. 1 and changes over the steam connections so that live steam is admitted through the pipe n to the reversing chamber f and through the pipe r^7 to the left-hand side of the dashpot piston e^5 , while the steam on the right-hand side of the dashpot piston passes out of the reversing space f^5 through the pipe n^1 , the chamber of the reversing valve t^2 and the port r^9 to the exhaust port r^{11} . The parts are now in the position shown in Fig. 1.

The adjusting means for the cams y and y^1 for varying the cut-off comprise a sleeve w^3 which is splined to the cam-shaft w , so as to revolve with the shaft and to be axially displaceable thereon, the cams y and y^1 being mounted on said sleeve and prevented from axial displacement thereon by means of spacing rings w^{20} . The sleeve w^3 has a helical groove for each of the cams y , y^1 , only one of said grooves being shown for the sake of clearness. The cams are provided with keys which engage in the respective grooves so that the cams rotate with the sleeve and the shaft w . The sleeve is displaceable axially by means of a lever w^{21} which engages a groove w^{22} on the sleeve. When the sleeve w^3 is slid axially by means of the lever w^{21} , the cams y , y^1 , owing to the engagement of the keys thereof with the helical grooves, are turned in the same direction so that they will open the valves s^1 , s^2 earlier or later in accordance with the angular position into which they have been adjusted.

Hence it will be seen from the foregoing that by adjusting the cams y , y^1 on the shaft w that open the admission control valves s^1 and s^2 , accurate regulation of the cut-off to the working cylinder is obtained.

The positively driven distributing slide valve t^1 is constructed with small laps, like the reversing valve t^2 , which, by interchanging the control pipes, determines the direction of rotation of the engine.

As will be seen from Figs. 1 to 4, the differential pistons, which are fixed on the slide valve rod with the parts d^1 and d^2 of the slide valve, are made considerably smaller in diameter than the latter. The size of these pistons is determined according to the maximum velocity of the engine in question, and the steam pressure available.

Since the inertia forces of the slide valve are taken up by steam cushions in the end positions and also in the cut-off positions, by suitable arrangement of the steam supply pipes as shown by the figures, noiseless working of the valve gear is ensured under all operating conditions and at all speeds.

What I claim is:

1. In a reciprocating steam engine, the combination with a steam cylinder and a piston movable therein, a slide valve casing having inlet and exhaust ports in open communication with said cylinder, a main slide valve movable in said slide valve casing and adapted to cover and uncover said ports for controlling the admission to and exhaust of steam from said cylinder and comprising two pairs of differential pistons, of conduits for supplying steam to one of the differential pistons of each pair for moving the slide valve into an initial, steam cut-off position and conduits for supplying steam to the other differential piston of each pair for moving the slide valve further into a terminal position for admitting steam to the opposite end of the cylinder, controlling valves interposed in the said steam supplying conduits for controlling the supply of steam to the said differential pistons, said controlling valves being operatively connected to the engine piston so as to be positively actuatable thereby, as and for the purposes set forth.

2. In a reciprocating steam engine, the combination with a steam cylinder and a piston movable therein, a slide valve casing having inlet and exhaust ports in open communication with said cylinder, a main slide valve movable in said slide valve casing and adapted to cover and uncover said ports for controlling the admission to and exhaust of steam from said cylinder and comprising two pairs of differential pistons, each pair comprising a larger piston and a smaller piston, of conduits for supplying steam to the larger piston of each differential piston for moving the slide valve into an initial, steam cut-off position, controlling valves interposed in said steam supplying conduits for controlling the supply of steam to said larger pistons, said controlling valves being operatively connected to the engine piston so as to be positively actuatable thereby, conduits for supplying steam to the smaller piston of each differential piston for moving the slide valve into a terminal position for admitting steam to the opposite end of the cylinder and a slide valve operatively connected to the piston, so as to be positively actuatable thereby, interposed in the steam supplying conduits for the said smaller pistons, as and for the purposes set forth.

3. In a reciprocating steam engine, the combination with a steam cylinder and a piston movable therein, a slide valve casing having inlet and exhaust ports in open communication with said cylinder, a main slide valve movable in said slide valve casing and adapted to cover and uncover said ports for controlling the ad-

mission to and exhaust of steam from said cylinder and comprising two pairs of differential pistons, each pair comprising a larger piston and a smaller piston, of conduits for supplying steam to the larger piston of each differential piston for moving the slide valve into an initial, steam cut-off position, controlling valves interposed in said steam supplying conduits for controlling the supply of steam to said larger pistons, a camshaft, means operatively connected to said camshaft and to the engine piston for imparting rotary movement to the camshaft, cams on said camshaft operatively connected to said controlling valves for actuating said valves, conduits for supplying steam to the smaller piston of each differential piston for moving the slide valve into a terminal position for admitting steam to the opposite end of the cylinder and a slide valve operatively connected to the piston, so as to be positively actuatable thereby, interposed in the steam supplying conduits for the said smaller pistons, as and for the purposes set forth.

4. In a reciprocating steam engine, the combination with a steam cylinder and a piston movable therein, a slide valve casing having inlet and exhaust ports in open communication with said cylinder, a main slide valve movable in said slide valve casing and adapted to cover and uncover said ports for controlling the admission to and exhaust of steam from said cylinder and comprising two pairs of differential pistons, each pair comprising a larger piston and a smaller piston, of conduits for supplying steam to the larger piston of each differential piston for moving the slide valve into an initial, steam cut-off position, controlling valves interposed in said steam supplying conduits for controlling the supply of steam to said larger pistons, a camshaft, means operatively connected

to said camshaft and to the engine piston for imparting rotary movement to the camshaft, a sleeve axially displaceable on said camshaft and operatively connected thereto so as to be capable of turning with the camshaft, a helical groove in said sleeve, cams on said sleeve operatively connected to said controlling valves and having driving projections engaged with said helical groove, distance rings on said sleeve between said cams for preventing axial displacement of the cams, conduits for supplying steam to the smaller piston of each differential piston for moving the slide valve into a terminal position for admitting steam to the opposite end of the cylinder and a slide valve operatively connected to the piston, so as to be positively actuatable thereby, interposed in the steam supplying conduits for the said smaller pistons, as and for the purposes set forth.

5. In a reciprocating steam engine, the combination as set forth in claim 1 with a reversing slide valve interposed in the steam supplying conduits for the smaller pistons for controlling the supply of steam to the controlling valves for controlling the supply of steam to the different pistons. 95 100

6. In a reciprocating steam engine, the combination as set forth in claim 1 with a working chamber in the valve casing, a hollow dashpot piston slideable in said working chamber, an auxiliary piston on the end of the main slide valve, 105 said auxiliary piston being passed into the interior of the dashpot piston with clearance so as to be slideable therein and pipes connected to the opposite ends of said working chamber 110 and to the conduits for supplying steam to the differential pistons, as and for the purposes set forth.

FRITZ TOLKIEN.
